LUMINAIRE SUPPORT

Hendrik A. J. de Vos, Wenham, Mass., assignor to Sylvania Electric Products Inc., a corporation of Delaware

Filed Apr. 26, 1965, Ser. No. 84,959

Term of patent 14 years

(Cl. D48—31)

FIG. 1

FIG. 2

FIG. 3

FIG. 4

FIG. 5

FIGURE 1 is an elevational view of a luminaire support showing my new design as viewed from one side thereof.

FIGURE 2 is an elevational view of the other side thereof.

FIGURE 3 is a top view thereof.

FIGURE 4 is a bottom view thereof.

FIGURE 5 is a front view thereof.

The broken line showings of a post at the rear end and an optical assembly at the front end are for illustrative purposes only.

I claim:

The ornamental design for a luminaire support, as shown and described.
